JOSEPH B. HOHMANN

By Watson E. Coleman

Attorney

UNITED STATES PATENT OFFICE.

JOSEPH B. HOHMANN, OF EUREKA, CALIFORNIA.

HOSE-SUPPORTER.

1,261,027.

Specification of Letters Patent.

Patented Apr. 2, 1918.

Application filed July 23, 1917. Serial No. 182,274.

To all whom it may concern:

Be it known that JOSEPH B. HOHMANN, a citizen of the United States, residing at Eureka, in the county of Humboldt and State of California, has invented certain new and useful Improvements in Hose-Supporters, of which the following is a specification, reference being had to the accompanying drawings.

10 This invention relates to hose supporters, and particularly to the clamp carried by the supporter and which engages the stocking.

15 The general object of the invention is to provide a stocking clamp of this character so constructed that there will be no such strain on the stocking as will cause it to wear or tear.

20 And a further object in this connection is to provide a stocking grip or clamp which exerts a straight pull on the stocking.

A further object is to provide means for exerting a double grip upon the stocking at two opposite points.

25 Other objects will appear in the course of the following description.

My invention is illustrated in the accompanying drawings, wherein:—

Figure 1 is a view of my supporter clamp in applied position;

30 Fig. 2 is a front elevation of the clamp and a portion of the supporter;

Fig. 3 is a longitudinal sectional view of the construction illustrated in Fig. 2;

35 Fig. 4 is a perspective view of a portion of the frame 10 and the locking member 12 showing the bearing and trunnion for the locking member;

Fig. 5 is a face view of the socket and the adjacent portion of the frame 10;

40 Fig. 6 is a face view of a portion of the frame 12 showing the trunnion;

Fig. 7 is a top plan view of the construction shown in Fig. 4, and Fig. 8 is a fragmentary plan view of the stocking engaging device, the lug 22 being in section.

45 Referring to these drawings, it will be seen that my improved grip comprises an outer rectangular frame 10 of metal, preferably round in cross section, which is formed at its middle with the laterally extending sockets 11 forming bearings for a clamping member 12, which is likewise approximately rectangular in plan view and which, intermediate its ends, is formed with laterally 50 projecting trunnions 13. By reference to

Fig. 4 it will be seen that these trunnions are not formed of members which extend directly outward so as to rotate freely in the bearings or sockets 11, but that the trunnions are each formed with a portion 14, which is 60 normally within a slight groove 15 formed in the member 10 rearward of the socket 11. The clamping member 12 is rectangular in form as before stated and preferably formed of resilient wire.

65 Attached to the cross bar 16 of the frame 10 in any suitable manner is an elongated loop 17, to which the web 18 is attached. This loop 17 is connected to the cross bar 16 by means of a clamping strip 19, which is 70 bent to surround the cross bar 16 and the cross bar of the loop 17. Surrounding the clamping member 19 is one end of a strip of elastic webbing 20 carrying at its free end the locking member 21 which is composed of 75 a strip of rubber into which the free end of the web 20 is embedded, this member 21 having, extending outward from its face, an approximately square stud 22. The outer face of this stud is undercut as at 23 and 80 the inner face of the stud is also undercut as at 24. The stud 22 has approximately the same width as the locking member 12.

85 In the practical use of this device, a portion of the stocking or other article to be supported is disposed over the stud 22, the frame 10 is then brought down over the portion of the stocking and flat against the base 21 and over the stud, and then the locking member 12 is turned downward from 90 the position shown in dotted lines until the locking member engages within the undercut portion 24 of the stud in the manner illustrated in Fig. 3. When the locking member is so engaged, it forces the end 95 cross bar 10^a of the frame 10 into the undercut 23 and the parts are locked in position and the stocking securely gripped between the end cross bar 10^a and the adjacent cross bar of the locking member 12. I have made 100 the locking member 12 of spring wire in order that it may spring into the undercut groove 24 when closed and the cross bar 12^a constitutes a thumb rest by which the locking member may be easily pressed down 105 with the thumb into locking position.

110 By reference to Fig. 3, it will be seen that when the stocking is first disposed over the stud 22, the frame 10 and the locking member 12 are disposed as illustrated in

dotted lines in Fig. 3 and then by forcing inward on the frame 10 and the locking member 12, the parts are readily forced to the full line position and the locking member 12 is disposed in the same plane as the frame 10, so that the fins 14 on the locking member will spring into the recesses 15 on the frame 10 and the parts be held in their locked position. By forcing outward on the locking member the fins may be disengaged from the recesses and the parts may be turned to the dotted line position to release the stocking.

The advantages of this clamp or grip 15 reside in the fact that there is no strain on the corners of the stocking or other article whatsoever, but that the clamp has a straight pull. There is no tendency with this device to strain the meshes of the fabric 20 and thus cause it to tear and the pull is entirely straight and not on the corners of the fabric. It will be noted that the corners of the stud 22 are rounded as at 25, thus making it impossible for any strain to 25 come on the fabric at these points.

By reference to Fig. 8 it will be seen that the four under corners of the stud, that is the four corners of the stud beneath the top of the stud are cut in so that when the 30 supporter clamp is in applied position, as in Fig. 8, the stocking is perfectly loose at the corners and the cross bar on the locking member 12 does not come out far enough laterally to rip the stocking at the corners. 35 There is some strain on the top of the stocking at the stud just enough to make it springy at that place and take the strain off of the meshes at the cross bar 10^a. In my supporter what strain there is is evenly 40 distributed over about 12 or 14 meshes of the stocking, whereas on other supporters known to me, the strain is not equal on all the meshes. There is more strain on two or three meshes in front of the button than 45 there is on the sides.

While I have illustrated the particular embodiment of my invention, I wish it understood that various changes in the details

of the device may be made, without departing from the spirit of the invention.

50

Having thus described my invention, what I claim is:—

1. A clamp for supporters of the character described comprising a rectangular frame having sockets between its ends, a strip of fabric attached to one end of the frame and carrying at its free end a stud adapted to extend through the frame, the stud having undercut oppositely disposed faces, with one of which undercuts the adjacent cross bar of the frame engages, and a locking member pivoted in said sockets and having a cross bar engaging in the adjacent undercut of the stud.

2. A clamp for supporters of the character described comprising a rectangular frame having sockets between its ends, a strip of fabric attached to one end of the frame and carrying at its free end a stud adapted to extend through the frame, the stud having undercut oppositely disposed faces, with one of which undercuts the adjacent cross bar of the frame engages, and a locking member pivoted in said sockets and having a cross bar engaging in the adjacent 70 undercut of the stud, said stud being made of rubber and having rounded corners.

3. A clamping device of the character described comprising a rectangular frame of metal having sockets intermediate its ends, a rectangular locking member made of spring wire having trunnions engaging in said sockets and having a cross bar, a flexible strip of webbing attached to one end of the frame, a rubber stud having a base attached to the free end of the webbing, the stud being approximately rectangular but having rounded corners and opposite undercut faces, the adjacent cross bar of the frame engaging any one of said undercuts, and a locking member engaging in the opposite undercut.
